JARRING TOOL

Fred N. Osmun, Houston, Tex.

Application January 21, 1938, Serial No. 186,041

10 Claims. (Cl. 255—27)

This invention relates to a jarring tool.

An object of the invention is to provide a tool of the character described whereby pipe stuck in a well bore may be jarred loose and thus recovered.

The type of tool herein described may be properly termed an inertia bar for the reason that it embodies one, or more, freely mounted projectiles mounted to be projected, by inertia, against an opposing impact face, or faces, whereby to create a jarring effect.

Another object is to provide in a tool of the type specified means for preventing the distortion of the operative end of the projectile, or inertia bar, and the corresponding impact face.

In one embodiment of the invention the projectile, or inertia bar, or hammer, is mounted so that, when projected, it will also be caused to rotate to the end that the member carrying the impact face will receive the force of the blow so as to not only cause a jarring action but a partial rotation of the impact receiving member; and inasmuch as the impact receiving member is connected to the stuck pipe in the well the pipe will be partly rotated and as a result of successive impacts a section, or sections, of the pipe may be unscrewed so that they may be removed in case the entire stuck pipe cannot be dislodged and removed as a result of the jarring action.

In another embodiment of the invention the tool is equipped with a plurality of projectiles, or inertia bars, or hammers, arranged to strike opposing impact faces successively at a single operation of the tool and without resetting the tool.

With the above and other objects in view the invention has particular relation to certain novel features of construction, operation and arrangement of parts, an example of which is given in this specification and illustrated in the accompanying drawings, wherein:—

Figure 1 shows a side elevation, partly in section, showing the upper end of the tool.

Figure 2 shows a side view, partly in section, of the lower end thereof.

Figure 3 shows a side elevation, partly in section, of a grapple adapted to be attached to the lower end of the tool and to engage the stuck pipe.

Figure 4 shows a side view, partly in section, of the complete jarring tool, including the grapple.

Figure 5 shows a side view, partly in section, of the upper end of another embodiment of the invention.

Figure 6 shows a side view, partly in section, of the lower end thereof.

Figure 7 shows a side view, partly in section, of the pipe grapping tool similar to, and for the same purpose as, that shown in Figure 3.

Figure 8 shows a cross-sectional view taken on the line 8—8 of Figure 6, and

Figure 9 shows a side elevation, partly in section, of the complete tool and grapple illustrating the embodiment shown in Figures 5, 6 and 7.

Referring now more particularly to the drawings wherein like numerals of reference designate the same parts in each of the figures, the numeral 1 designates the outer housing, or shell, of a jar threaded into the upper end of which there is a gland 2 whose lower end presents an annular impact face 3 and extended through the gland there is a tubular mandrel 4 whose upper end is connected to an operating string 5 by means of suitable couplings 6, 6a. The lower end of the coupling 6 abuts the upper end of the gland 2 when the tool is set, as hereinafter referred to, so as to limit the downward movement of the mandrel in the shell.

On the inside of the shell there are a plurality of vertical ribs 7, spaced apart around the shell as more clearly shown in Figure 8. The upper ends of these ribs terminate the required distance beneath the impact face 3.

At the lower end of the mandrel 4 there are the vertical ribs 8 which extend out radially from the mandrel and work between the ribs 7 as illustrated in Figures 2 and 6. The upper end of each rib 8 presents an upwardly facing flat face 9 adapted to strike against the impact face 3 of the gland 2.

The ribs 7, 8 are releasably locked in set position by the upwardly tapering lugs 10 on the upper end of the cylinder 11 which is seated on a strong coil spring 12 and which works in the cylinder 13 filled with liquid. There is an inside coupling 14 screwed into the lower end of the housing 1 and to the lower end of this coupling a suitable grapping tool such as 15 is attached. This grapping tool is engageable with the pipe 16 stuck in the well.

The Jar, hereinabove described, is more specifically disclosed in my co-pending application, Serial No. 186,040, executed on the 21st day of January, 1938, and the grapping tool hereinabove referred to is more specifically described in the co-pending application of myself and Frank Kinzbach executed on the 11th day of October, 1937, which are here referred to and for that reason need not be more specifically herein referred to.

When the jarring tool, illustrated in either embodiment as described, is lowered into the well and the grappling tool is engaged with the stuck pipe an upward pull is exerted through the operating string placing the tool under tension and thereupon the piston 11 will yield and move downwardly releasing the ribs 8 and permitting them to clear the lower ends of the ribs 7 and thereupon the upper section of the tool will, on account of the elasticity of the operating string, suddenly move upwardly and the upper ends of the ribs 8 will strike against the impact face 3 thus suddenly stopping the relative longitudinal movement of said parts and creating a jar, all as described in my said co-pending application for Jar.

It is to be understood, however, that any type of grappling tool may be used for engaging the stuck pipe or any conventional type of jar may be substituted for that shown and hereinabove more specifically described.

Incorporated into the operating string the required distance above the coupling 6a there are the inter-connected couplings 17, 18 and incorporated into said string above the coupling 18 there are the inter-connected couplings 19, 20 as shown in Figure 1. That portion of the operating string extending on to the ground surface may be connected to the last mentioned coupling 20. There are the wash pipe sections 21, 22, 23. The lower end of the section 21 is screwed into the coupling 18 and extends up through the coupling 19 and is packed by the annular packing 24 which surrounds said section 21 and is countersunk into the coupling 19 and is maintained expanded by the gland 25. The wash pipe section 22 is screwed into the coupling 6a and extends up through the coupling 17 and is surrounded by the packing 26 which is countersunk into the coupling 17 and maintained compressed by the gland 27. The section 23 of the wash pipe is screwed into the upper end of the coupling 14 and extends on up into the coupling 6a and is surrounded by the packing 28 which is maintained expanded by the gland 29 screwed into the upper end of the mandrel 4. A washing fluid may be forced down through the operating string and through said wash pipe and on down through an axial channel through the grappling tool to wash out the well or to wash out the upper end of the stuck pipe ahead of the tool.

It will be noted that the wash pipe sections 21, 22 are spaced inwardly from the operating string proper and surrounding said wash pipe sections 21, 22 and normally resting on the respective couplings 18 and 6a are the inertia bars, or projectiles 30, 31. These are tubular in form and are mounted for free movement.

When the upper ends of the ribs 8 strike the impact face 3, as hereinabove provided, the upward movement of the upper section of the tool, that is, of the operating string, will be suddenly stopped. The inertia bars, or the projectiles 30, 31 will move upwardly with the operating string at high speed and when this upward movement of the string is suddenly stopped the momentum of the projectiles will cause them to travel on upwardly striking the opposing lower ends of the couplings 19, 17, respectively, with great force. The distance between the upper end of the bar 31 and the lower end of the coupling 17, as shown, is greater than the distance between the upper end of the inertia bar 30 and the lower end of the coupling 19 so that these strokes, above referred to, will be delivered suc-

cessively and these successive jars, will in an obvious manner, be transferred to the stuck pipe and will usually be effective to dislodge it so that it may be withdrawn from the bore.

It is obvious that a single inertia bar, or projectile, may be used or a plurality of them if desired.

In the embodiment illustrated in Figures 5 to 9, inclusive, a female tool joint coupling 32 is screwed into the upper end of the coupling 6 and 10 screwed into the upper end of the coupling 32 there is the tubular section 33 of the operating string. The portion of the operating string 34 above is connected to the section 33 by means of a coupling 35 whose lower downwardly facing end 15 is formed into an impact face 36 having a depending lug 37. In this form there is an outside, tubular inertia bar 38 fitted around the section 33 and normally resting on the upper end of the female coupling member 32 and whose upper end 20 is normally spaced beneath the impact face 36. The inertia bar, or projectile 38 is connected for a sliding and rotative movement with the section 33 by means of a spiralled spline 39. As shown this spline is spiralled to the right so that 25 upon upward movement of the inertia bar 38 it will rotate to the left. The upper end of the inertia bar 38 is provided with a lug 40 pitched in a direction the opposite of that of the lug 37. The lugs 31, 40 have the opposing contact faces 30 41, 42.

Upon release of the jar, shown in Figure 6, and the upward movement of the upper sections of the tool, in response to the elasticity of the operating string and upon contact of the faces 9 35 with the faces 3 and the sudden stopping of the relative longitudinal movement of said sections the inertia bar 38 will continue to move on upwardly. The arrangement and pitch of the spline 39 is such that when the upper end of the inertia bar 38 strikes the impact face 36 the face 42 will also strike against the face 41 with a sudden blow thus creating a jar and also partially rotating the tool to the left. This left-hand rotation will be imparted through the clutch 45 formed by the ribs 7 and 8 to the grapple 15 and thence to the stuck pipe 16 thus imparting a left-hand thrust, or turning movement, to said pipe and a repetition of the operation may either jar the stuck pipe loose or unscrew a joint beneath 50 of the stuck pipe permitting the withdrawal of the unscrewed portion of the stuck pipe from the well.

In order to protect the impact face means have been provided for temporarily trapping a liquid 55 cushion between the impact face and the opposing end of the corresponding inertia bar 30 or 31. For this purpose the lower ends of the couplings 17, 19 are provided with the annular channels 43, 44, as shown in Figure 1 which diverge, slightly, 60 downwardly. The operating string is provided with openings 45, 46 whereby the well fluid may enter the chambers in which the projectiles or inertia bars are located and upon projection of said bars upwardly their upper ends will enter 65 the channels 43, 44 and will temporarily trap the fluid in said channels which will act as cushions to prevent the battering or marring of the upper ends of the inertia bars as well as the impact faces, said entrapped liquid being ultimately permitted to escape by reason of the downward flare 70 of said channels.

The drawings and description disclose what are now considered to be preferred forms of the invention by way of illustration only, while the 75

broad principle of the invention will be defined by the appended claims.

What I claim is:

1. A jarring tool comprising two relatively movable parts, means for releasably locking said parts against relative longitudinal movement, said locking means being releasable under the influence of tension on the parts to permit such relative longitudinal movement, means for arranging such relative longitudinal movement to cause a jar, means for connecting one of said parts to a stuck object, an inertia bar, forming a projectile carried by the other part mounted to be projected upon such relative longitudinal movement of said parts and an impact member arranged on said other part to receive the impact of said inertia bar upon such projection.
2. A jarring tool comprising two relatively movable parts, means for releasably locking said parts against relative longitudinal movement, said locking means being releasable under the influence of tension on the parts to permit such relative longitudinal movement, impact receiving members, means arranged to engage one of said impact members, upon release of said locking means, to arrest said longitudinal movement and cause a jar and means arranged to be thereafter projected against the other impact member to cause a jar.
3. A jarring tool comprising two relatively movable parts, means for releasably locking said parts against relative longitudinal movement, said locking means being releasable in the presence of tension on said parts to permit such longitudinal movement, means for arresting such relative longitudinal movement to cause a jar, means for connecting one part to a stuck object, an impact member on the other part and an inertia bar forming a projectile arranged to be projected against said impact member upon the arrest of such relative longitudinal movement of said parts.
4. A jarring tool comprising two relatively movable parts, means for holding said parts against relative longitudinal movement while the tool is under tension and being releasable to permit such longitudinal movement, means for arresting such relative longitudinal movement to cause a jar, means for connecting one part to a stuck object, an impact abutment on the other part and means arranged to be projected against said abutment upon the arrest of such relative longitudinal movement of said parts.
5. A jarring tool comprising a tubular string having two parts and adapted to be placed under tension, means for preventing relative longitudinal movement of said parts, said means being releasable to permit such relative longitudinal movement under the influence of the tension on the string, means for arresting such longitudinal movement to cause a jar, means for connecting one of said parts to a stuck object, an impact abutment on the other part and a projectile carried by the string, a plurality of impact abutments carried by the string, a plurality of projectiles carried by the string and arranged to be projected against said abutments upon operation of the jarring tool.
6. In combination an operating string, a jarring tool incorporated into the string, means for connecting the jarring tool to a stuck object, a plurality of impact abutments carried by the string, a plurality of projectiles carried by the string and arranged to be projected against said abutments upon operation of the jarring tool.
7. In combination an operating string, a jarring tool incorporated into the string, means for connecting the jarring tool to a stuck object, a plurality of impact abutments carried by the string, a plurality of projectiles carried by the string and arranged to be projected to impact successively against the respective abutments upon operation of the jarring tool.
8. A jarring tool comprising two relatively movable parts, means for releasably locking said parts against relative longitudinal movement, said locking means being releasable while the tool is under tension to permit such relative longitudinal movement, means for arresting such relative longitudinal movement to cause a jar, means for connecting one part to a stuck object, an impact member on the other part, a body forming a projectile arranged to be projected against said impact member upon the arrest of such relative longitudinal movement of said parts and means for causing rotation of the projectile.
9. A tool of the character described adapted to be placed under tension and comprising two relatively movable parts, means for holding said parts against relative longitudinal movement, said means being releasable while said parts are under tension to permit such longitudinal movement, means for arresting such relative longitudinal movement to cause a jar, a grapple for connecting one of said parts to a stuck object, an impact abutment on the other part and a member arranged to be rotated, and simultaneously projected against said abutment, by the momentum of said member, upon the arrest of such relative longitudinal movement of said parts.
10. A jarring tool comprising a tubular string adapted to be placed under tension, means for connecting the string to a stuck object, an abutment carried by the string, a movable body arranged to be projected against said abutment to create a jar upon release of said tension, said abutment and the opposing end of said body being formed, one with a recess forming a trap for liquid into which the other projects upon operation of the tool.

FRED N. OSMUN. 60
